ACCIDENT PREVENTING BOTTLE CAP
 Walter V. Triglavcanin, 22 Drury Lane,
 Weston, Ontario, Canada
 Filed May 14, 1964, Ser. No. 367,490
 4 Claims. (Cl. 215—9)

This invention relates to a safety device for bottles.

The object of this invention is to protect children from poisoning by means of an accident preventing bottle cap to be used on bottles containing poisonous fluid or any other substances.

This invention will provide bottles with a safety device which can easily be removed by adults but cannot be removed by small children.

A further object of this invention is its easy application to existing bottles.

This invention is shown in the accompanying drawings wherein:

FIGURE 1 is a section of the line I—I of FIG. 2;
 FIG. 2 is a section II—II of FIG. 1;
 FIG. 3 is an enlarged section of the releasing device;
 FIG. 4 is a section of the line IV—IV of FIG. 2;
 FIGURE 5 is an enlarged plan view of the releasing device;
 FIG. 6 is an enlarged section VI—VI of FIG. 4;
 FIG. 7 is an enlarged section VII—VII of FIG. 4.

The accident preventing bottle cap consists of a removable cap A and a seat B.

The removable cap A comprises: casing 1, stopping ring 2, perimeter casing groove 3, spring tightening screw with washer and nut 4, guiding plate 5, contact guides 6, leaf springs 7, push buttons 8, and flexible covering 9.

Seat B consists of: interlocking ring 10, contact rubber heads 11, attaching screws 12, compressible gasket 30, 13, and peripheral stop groove 14.

The radially placed rubber-headed attaching screws, shown by the numeral 12, are used for fastening the seat B to the throat of the bottle. The inside of the upper part of the interlocking ring 10 is shaped to interlock the leaf springs 7 of the removable cap A. A perforated compressible gasket 13 sits in the peripheral stop groove 14 to function as a spring.

On the inside of the removable cap leaf springs 7 are attached symmetrically by the guiding plate 5 and spring tightening screw, washer, and nut 4. On the outside of the removable cap A pushbuttons 8 are located radially to the centre. Said pushbuttons are hidden by a flexible covering 9 which is pressed tightly into the perimeter casing grooves 3.

In order to attach the accident preventing bottle cap to the bottle the seat B has to be fastened to the bottle neck by tightening the rubber-headed 11 screws 12 below the existing ordinary bottle cap. Said seat remains fastened to the bottle at all times while the removable cap A must be removed in order to reach the ordinary bottle cap.

Seat B can be made without rubber-headed 11 screws 12 if said seat is incorporated in the bottle neck.

2

The removable cap A can be interlocked with the seat B by slight downward pressure on the cap whereupon leaf springs 7 will be forced towards the centre and will slide towards the inside groove of interlocking ring 10.

5 When the bottom rim of cap A reaches gasket 13 additional pressure should be applied compressing gasket and allowing spring 7 to interlock with interlocking ring 10. Removable cap A is now sitting in the locked position and the interlocking springs 7 resist any pulling force, preventing the lifting off of removable cap A.

To remove cap A reverse pressure should be applied e.g. instead of pulling off the cap, it should be pressed down. At the same time all the pushbuttons have to be depressed by pressure on the flexible covering whereupon 15 the inside end of the button will press the spring in a radial direction and thereby spring 7 will be released over the top of the interlocking groove seat and the removable cap A can be lifted up.

The embodiments of the invention in which an exclusive property or privilege is claimed are defined as follow:

1. An accident preventing bottle cap for a bottle and the like having or being without an ordinary bottle cap, which accident preventing bottle cap comprises: a removable cap having internally located and outwardly protruding V-shaped locking springs leaned on and released by pushbutton, and a locking seat internally shaped to interlock with said locking springs, said locking seat being adapted to be fastened to the neck of said bottle or to be incorporated in the neck of said bottle.

2. An accident preventing bottle cap as defined in claim 1 in which the removable cap has pushbuttons on the perimeter of its casing radially located and hidden by a flexible covering whereby said pushbuttons have the function to release the locking springs and thereby disconnect the removable cap from the interlocking seat.

3. An accident preventing bottle cap as mentioned in claim 1 in which the removable cap has internally located and outwardly protruding V-shaped locking springs, leaned on and released by pushbuttons, to interlock said cap to said seat by outward movement of said springs.

4. An accident preventing bottle cap as defined in claim 1 in which the locking seat has on the outside in a peripheral stop groove a compressible gasket to function as a spring by uplifting removable cap and thereby interlocking springs of removable cap to interlocking seat.
